[57] CLAIM

The ornamental design for a combined display and packaging container for self-adhesive labels or the like, as shown and described.

DESCRIPTION

FIG. 1 is a perspective view of a combined display and packaging container for self-adhesive labels or the like showing my new design;

FIG. 2 is a perspective view in a hanging position;

FIG. 3 is a perspective view in a standing position; and

FIG. 4 is a perspective view showing the side opposite that seen in FIG. 3.
